UNITED STATES PATENT OFFICE.

LOUIS G. RINK, OF CHICAGO, ILLINOIS, ASSIGNOR TO SHARP & SMITH, OF CHICAGO, ILLINOIS, A CORPORATION OF ILLINOIS.

SACRAL REST.

1,258,246.

Specification of Letters Patent.

Patented Mar. 5, 1918.

Application filed September 28, 1917. Serial No. 193,618.

To all whom it may concern:

Be it known that I, LOUIS G. RINK, a citizen of the United States, residing at 155-157 North Michigan Ave., Chicago, in the county 5 of Cook and State of Illinois, have invented a new and useful Improvement in Sacral Rests, of which the following is a specification.

My invention relates to certain new and 10 useful improvements in sacral rests, and is fully described and explained in the specification and shown in the accompanying drawing, in which:

Figure 1 is a side elevation of my device 15 as used; Fig. 2 is a central longitudinal section, and Fig. 3 is an end view of the device.

Referring to the drawing; 4 is a base supporting a post, 5, upon which is mounted a vertically adjustable sleeve 6 which may 20 be locked at various heights by a screw 7 engaging depressions in the post. The sleeve has a rounded upper end 8; 9 is the rest proper, the same having a curved portion fitting the spine and an upwardly projecting tip 10, like the horn of a saddle. This tip fits over the rounded upper end 8 of the sleeve 6 and may be engaged by a set-screw 11 in the post to be set at various 25 angles thereon.

The device finds its principal usefulness in 30 applying plaster bandages in case of injuries to the hips and thighs. The patient is supported well above the level of the table by pillows, or the like, under the shoulders. The rest proper is placed in position with its 35 main portion supporting the lower end of the back and the tip or horn projecting up between the legs. The patient's legs may be supported at a level with the body in any 40 desired manner. The present device thus affords a clear space underneath the body at about the sacral line and it is, therefore, very easy to bandage the patient, since the bandage can be passed around and around the 45 trunk without difficulty. When the bandage is in place the rest can be removed in a forward and upward direction, its curvature

and the tapered form of its tip permitting it to slide readily from beneath the bandage. The rest proper may be easily removed from 50 the sleeve for cleaning.

I realize that considerable variation is possible in the details of the construction herein shown, and I do not intend to limit myself thereto, except as pointed out in the 55 following claims, in which it is my intention to claim all the novelty inherent in the device as broadly as is permitted by the state of the art.

What I claim as new and desire to secure 60 by Letters Patent, is:

1. A sacral rest comprising a base, a support rising therefrom, and a rest proper mounted to rock on said support and curved to fit the spine and having an upwardly 65 curved tip adapted to lie between the legs of the patient.

2. A sacral rest comprising a rest proper tapered at one end and curved to fit the spine of the patient and having an upwardly 70 projecting tip at its opposite end to lie between the legs of the patient, a base, and means connecting the tip of the rest proper with the base to support the same in rocking relation thereto.

3. A sacral rest comprising a base, a rest proper curved to fit the spine and having an upwardly-projecting tip adapted to lie between the legs of the patient, and adjustable means of connection between the base and 80 rest proper for varying the height and lateral projection of the latter.

4. A sacral rest comprising a base, a post carried thereby, a sleeve vertically adjustable on the post, a rest proper tapered at one 85 end and curved to fit the spine and having an upwardly projecting tip adapted to lie between the legs of the patient and pivotally mounted upon the upper end of the sleeve, and means for swinging the rest proper 90 on the upper end of the sleeve at various angles.

LOUIS G. RINK.
